UNITED STATES PATENT OFFICE.

LESTER O. MELLOR, OF EVANSTON, ILLINOIS.

FUSE DEVICE.

1,173,598.

Specification of Letters Patent. Patented Feb. 29, 1916.

Application filed March 3, 1913. Serial No. 751,686.

To all whom it may concern:

Be it known that I, LESTER O. MELLOR, a citizen of the United States, residing at Evanston, in the county of Cook and State of Illinois, have invented a certain new and useful Improvement in Fuse Devices, of which the following is a full, clear, concise, and exact description, reference being had to the accompanying drawings, forming a part of this specification.

My invention relates to fuse devices, and especially to fuse devices in which the fuses are inclosed.

Prominent objects of the invention are to provide a simple, practical and inexpensive form of fuse device; to arrange for the extinguishment of the arc formed when the fuse blows; to prevent injury to the device and surrounding objects by the operation of the fuse; and to accomplish the foregoing and other desirable results in a simple and expeditious manner.

In the accompanying drawings Figure 1 is a vertical section of a fuse device embodying my present invention; Figs. 2 and 3 are horizontal sections of the same, taken on the lines 2-2 and 3-3 in Fig. 1; Figs. 4 and 5 are views of details of construction.

Referring to the drawings, I provide an exterior case 1 which is made of any desirable material, preferably porcelain or other insulating material. This case is in the form of an inverted socket with vertical cylindric walls and is shown in Figs. 2 and 3 open at its lower end. Said lower end is enlarged as shown in Figs. 1 and 2, and will be referred to more particularly hereafter. Within the socket 1 is a plug 2 also cylindric in form and adapted to fit within the cylindric bore 3 of the socket 1 so as to permit ready insertion and removal of the plug 2 into said socket 1. The plug 2 is provided at its lower end with a handle 4 by which said plug may be grasped by the hand, and said handle is extended from a cross portion 5 of relatively large size so that it closes the lower end of the enlarged bore 6 of the socket 1. The plug 2 is provided with metal clips 7-7 which have lateral projections 8-8 and the socket 1 is provided with spring socket members or jaws, 9-9 adapted to receive the lateral projections 8-8, said

members 9-9 being preferably in the form of sheet metal pieces 10-10, bent to form the laterally projecting horizontal spring 55 socket jaws 9-9, as shown in Fig. 4. The clips 7-7 are secured to the plug 2 by screws 11-11, and the spring socket members 9-9 are secured to the socket 1 by screws 12-12, said spring socket members 60 being arranged in the enlarged bore 6 of the socket member 1. Thus the plug 2 may be held in position in the socket 1 and contact also made between the two members by the engagement of the clip projections 65 8-8 with the socket members or jaws 9-9. This engagement and disengagement can be brought about by giving the plug 2 a small turn or twist by means of the handle 4 so as to slip the projections 8-8 into or out 70 of the sockets 9-9. The plug 2 carries a fuse 14 which is arranged in irregular form as best shown in Fig. 1. Said fuse is secured at its ends to the clips 7-7, as shown in Figs. 1 and 5, and extends thence upwardly and across the top of the plug 2 and thence downwardly within the bore 15 thereof, and across the same as shown in Fig. 1. The lower cross portion of the fuse in said bore 15 is reduced or narrowed 75 as shown at 16, Fig. 3. The bore or chamber 15 is desirably provided with oil or other arc extinguishing liquid 17, which of course has the effect of submerging or partly submerging the fuse 14. A loose 80 block 18 is fitted upon the top of the plug 2, said block 18 conveniently having a downward projection 19 which fits into bore 15 and extends part way down the same with space between said portion 19 and the walls 85 of the bore 15 sufficient to allow the fuse 14 to have its proper position. A spring 20 is interposed between the block 18 and the top of the socket 1, said spring 20 serving normally to hold the block 18 down and 90 tending to keep it in a downward position, so that it will close the top of the chamber 15.

Thus it will be seen that when the device is in normal position the fuse 14 is bent 100 twice double between its terminals, extending first up and then down, and that barriers are interposed between the rising portions and also between the depending por-

tions so that a very irregular path tending to obstruct the arc is provided. It will be further seen that the narrowed or reduced portion of the fuse which of course is that portion which will first blow, is well within the device, being farthest from the terminals and best projected by the barriers and also is immersed in oil or other suitable liquid. It will also be seen that this reduced or most susceptible part of the fuse is practically inclosed, the block 18 forming a substantial closure for the bore 15 of the plug 2 whereby the arc is well confined and also that sufficient yield to accommodate any explosion of the fuse is provided by the movability of one of the walls, as for example the block 18 of the confining chamber thereby preventing damage from the explosion of the fuse. It will also be seen that this movable or yieldable portion of the confining wall is automatically restored to place and held with a proper amount of tension against movement so that the fuse and liquid therefor are not unduly dissipated, but are sufficiently confined to prevent scattering and other undesirable effects. It will further be seen that when the fuse has operated it can be replaced by simply detaching and removing the plug 2 and putting a new fuse and new liquid if necessary in the same.

It will be understood that changes and modifications can be made without departing from the spirit of the invention.

What I claim is:

35. 1. A fuse device comprising plug and socket members, the socket member being open at its lower end and the plug being insertible into the socket member from below, said plug being provided with a centrally arranged chamber and carrying a fuse which is connected to the outer walls of the plug and extends thence upwardly and then inwardly and downwardly in said chamber, arc extinguishing liquid in said chamber submerging a portion of said fuse, a closure 18 mounted upon the upper end of the plug and closing the chamber thereof, and spring means interposed between said closure and the top of the socket member.

50. 2. A fuse device comprising plug and socket members, whereof the socket member is provided with an opening whose mouth is at its lower end and the plug member being arranged to be inserted upwardly into said opening, said plug member being provided with a chamber open at its top, a fuse having its terminals secured to the sides of said plug member and extended downwardly into said chamber, and arc extinguishing liquid in said chamber submerging the lower portion of said fuse therein.

3. A fuse device comprising plug and socket members, whereof the socket member is provided with an opening whose mouth is at its lower end and the plug member being arranged to be inserted upwardly into said opening, said plug member being provided with a chamber open at its top, a fuse having its terminals secured to the sides of said plug member and extended downwardly into said chamber, arc extinguishing liquid in said chamber submerging the lower portion of said fuse therein, and a closure for the upper end of said chamber in said plug.

4. A fuse device comprising plug and socket members, whereof the socket member is provided with an opening whose mouth is at its lower end and the plug member being arranged to be inserted upwardly into said opening, said plug member being provided with a chamber open at its top, a fuse having its terminals secured to the sides of said plug member and extended downwardly into said chamber, arc extinguishing liquid in said chamber submerging the lower portion of said fuse therein, and a closure for the upper end of said chamber in said plug, said closure having a projection extending down into said chamber and interposed between downwardly extending portions of said fuse above said liquid.

5. A fuse device having an internally arranged chamber containing arc extinguishing liquid, a fuse led into the top of said chamber and extended downwardly along the opposite sides thereof and across the same below the top thereof, and a removable closure for said chamber resting upon the top of the walls of said chamber, and having a projection extending downwardly into said chamber.

105 6. A fuse device having an internally arranged chamber containing arc extinguishing liquid, a fuse led into the top of said chamber and extended downwardly along the opposite sides thereof, and across the same below the top thereof, a removable closure for said chamber resting upon the top of the walls of said chamber, and spring means tending to hold said closure in position to close said chamber.

110 7. A fuse device having an internally arranged chamber containing arc extinguishing liquid, a fuse led into the top of said chamber and extended downwardly along the opposite sides thereof and across the same, below the top thereof, a removable closure for said chamber resting upon the top of the walls of said chamber, and having a projection extending downwardly into said chamber and between the downwardly extending portion of the fuse, and

spring means acting upon the top of said closure and tending to hold the same downwardly in position to close said chamber.

8. In a fuse device the combination of a fuse carried by a member providing a fuse chamber, said fuse being extended down the opposite sides of said chamber and across the same below its top, a closure for said chamber, a barrier interposed between the side portions of said fuse, said barrier being formed by a downwardly extending

projection on said closure, and a spring acting upon said closure to hold the same normally in position to close said chamber.

In witness whereof, I hereunto subscribe 15 my name this 26th day of February, A. D. 1913.

LESTER O. MELLOR.
